FENCE STRUCTURE
Verino De Chellis, 250 Hyde Park Ave.,
Jamaica Plain, Mass.
Filed Sept. 17, 1963, Ser. No. 309,463
1 Claim. (Cl. 256—32)

This invention relates to a fence structure and more particularly to an improved chain link fence which has ornamental scrollwork affixed to its top edge. The scrollwork is positioned between a spaced apart pair of horizontal railings that protects the scrollwork and strengthens the overall fence structure. The railings pass through and are supported by a plurality of improved rail support caps seated upon the fence posts.

Chain link fences are commonly erected both on industrial property and on residential property. For industrial use, a chain link fence provides sturdy effective protection from theft and vandalism. It is relatively low in initial cost and is virtually maintenance-free. For residential use, a chain link fence allows the sunlight and breeze to pass through, yet effectively confines children, pets and their possessions. Furthermore, such a fence prevents outsiders from trespassing and keeps out stray animals and the like.

However, a problem which has always plagued the chain link fence industry is the reluctance of home owners to use chain link fencing because of its harsh inhospitable appearance. Owners of homes generally wish to present a less hostile facade, although at the same time they want the protection for their children and themselves that can best be obtained by the use of a chain link fence.

To solve this consumer acceptance problem there have been a few prior efforts to find ways to enhance the appearance of chain link fencing. All have failed. This invention solves this problem by providing a fence that is quite attractive and has novel features which strengthen the fence and at the same time protect the ornamental portions.

In brief, this invention employs vertical fence posts which are spaced apart and have chain link fencing material stretched therealong. The novel components include the provision of two horizontal railings in vertical spaced relationship which are carried at the top of the fence posts above the chain link material by means of novel rail support caps provided with rail openings at the upper and lower extremities thereof. Ornamental scrollwork is disposed between the railings and fastened thereto. The railings protect the scrollwork from damage and also increase the strength of the overall fence structure.

In accordance with the above, it is an object of this invention to provide a chain link fence structure which is attractive in appearance and acceptable to home dwellers, yet which in no way sacrifices those protective features long associated with chain link fences.

It is another object of this invention to provide a chain link fence structure having a pair of spaced apart horizontal railings carrying ornamental scrollwork therebetween, said railings acting to protect the ornamentation from damage due to ordinary wear and tear and the vandalism of passers-by.

It is a further object of this invention to provide a unique rail support cap structure which can be seated on the fence post and through which the spaced horizontal railings are supportably carried.

A still further object of this invention is to provide a fence structure which has increased structural rigidity due to its use of double horizontal railings carried in rail support caps having an I-beam cross-section.

Other objects and advantages of the invention will be

2

come apparent from a study of the accompanying drawings and descriptive matter in which is illustrated and described a preferred embodiment of the invention.

In the drawings:

5 FIG. 1 is an elevation of the fence structure incorporating the invention;

FIG. 2 is an enlarged view of a portion of FIG. 1 showing the double railing and rail support cap in detail; and

FIG. 3 is a view in perspective of the rail support cap with the seat portion partly broken away.

Referring now more particularly to the drawings, the fence structure, generally designated as 10, has a plurality of vertically extending heavy metal fence posts 12 which are securely embedded in the ground, indicated generally at 14. Posts 12 are preferably in alignment and are spaced approximately six to eight feet apart (however, wider spacing would be equally acceptable). The posts usually have a circular cross-section, although 15 the shape could be square, etc. Chain link fencing material 16 of linked steel construction shown in detail in FIG. 2, is stretched along the line of fence posts 12 for relatively long distances, or may alternatively be secured to approximately every third or fourth post as 20 shown in the drawings, depending on the length of fencing material furnished by the manufacturer and the terrain conditions.

The fencing material 16 is fastened to the fence posts 12 by means of securing bars 18 and post clamps 20. At 30 each end of the fencing material, a securing bar 18 is threaded through the edge loops. Post clamps 20 are secured to the corner fence posts 12 by fasteners 22 and optionally to every third or fourth post, if the terrain requires. The post clamps 20 are preferably vertically 35 spaced about eighteen inches apart. The securing bars 18 are pulled toward the post clamps 20 and affixed thereto by fasteners 25 on post clamp tip portions 23. In this fashion the fencing material 16 can be stretched between fence posts 12 and firmly held thereto. The fencing material 16 is prevented from shifting downwardly by means 40 which will be subsequently described.

Referring now to FIG. 3, the rail support cap, indicated generally at 24, has an integral seat portion 26 in the form of an inverted cup. Seat portion 26 has an internal circular seat base 28, cylindrical side walls 30 depending downwardly from the circumference of seat base 28, and a lower lip 32 formed at the bottom edge of side walls 30. The cross section of the cylindrical side walls 30 is shown in the cut away portion of FIG. 3. Seat portion 45 50 55 26 is dimensioned to permit the rail support cap to be securely seated upon the upper end of fence post 12, and the cylindrical side walls 30 are of sufficient vertical dimension to prevent accidental disengagement of the rail support cap from the fence post.

Rail support portion 34 is formed integral with and extends upwardly from seat portion 26. Rail support portion 34 has an I-beam shaped horizontal cross-section for strength and heavy rounded top and bottom portions 35 and 36. Extending through the top portion 35 is 60 upper rail sleeve 37 which is adapted to supportably carry a horizontal railing. Extending through bottom portion 36 is a lower rail sleeve 38 identical to upper rail sleeve 37.

A decorative sculptured ornament preferably extends 65 above the top portion 35, as for example the flame tip 40 shown in FIG. 3. This is an optional feature, but one that enhances the attractiveness of the fence structure. Obviously, the ornament could be cast in many other shapes, such as a ball, spear, cone, etc. The entire rail support cap 24 is preferably cast in one piece 70 and is structurally designed to have maximum rigidity

and strength characteristics. One rail support cap 24 is seated atop each fence post 12 after the fence posts and fencing material have been erected.

Upper and lower horizontal railings 42 and 44 preferably consist of long lengths of metal tubing or rod, approximately 1½ to 2 inches in diameter and 8 to 40 feet in length. Wherever the fence alignment is straight, each horizontal railing extends in an unbroken length the entire straight distance up to approximately 40 feet. The railings are supportably carried in their respective rail sleeves 36 and 38 which are dimensioned to allow a circumferential clearance of approximately $\frac{1}{64}$ inch. At the fence corners, the railings terminate and are engaged by conventional post clamps (not shown), similar to post clamps 20, but having cupped receiving means at their tip portions for holding the railing ends. The railings 42 and 44 are vertically spaced apart about 5 to 6 inches and are in parallel vertical alignment throughout their entire length.

To prevent the chain link fencing material 16 from sliding down the fence posts 12 or drooping away from lower horizontal railing 44, a plurality of thin wire strips 45 are looped around the upper links of fencing material 16 and secured to lower horizontal railing 44 at spaced horizontal intervals. The wire strips 45 bind the fencing material tightly to the railing to help create a neat appearing fence structure.

Decorative scrollwork 46, shown in FIG. 1, is preferably formed of wrought iron. One attractive pattern shape is illustrated. Others could be substituted according to consumer preference. The scrollwork is mounted between the upper and lower horizontal railings 42, 44 by means of a plurality of fasteners 48. These fasteners preferably have a C-shape with a tab 50 that is welded or bolted to the scrollwork 46. The scrollwork 46 is secured to the railings by hammering or bending the C-shaped fasteners 48 around the railings. The fasteners tightly grip the railings and will not loosen accidentally. It will be seen in FIG. 1 that one scrollwork unit is fastened between each adjacent pair of railing support caps 24. The scrollwork 46 can be of varying lengths selected to correspond to the spacing between the railing support caps 24.

From the above description it will be appreciated that the novel features of this invention cooperate to achieve a fence structure that is attractive and has increased strength. The scrollwork which is the principal attractive feature is protected by the double railings which also act to increase the strength of the fence.

To assemble the fence, the fence posts 12 are first embedded in the ground 14 at spaced intervals and in maximum alignment. Fencing material 16 is then strung between the posts in the longest lengths possible. At each end edge of the fencing, a securing bar 18 is inserted and several post clamps 20 are attached to the securing bar with fasteners 25. The post clamps are then

slipped over the fence post 12 and secured tightly there to by means of fasteners 22.

Rail support caps 24 are seated upon the top of each fence post 12 and turned so that the axes of the rail sleeves 37, 38 are aligned with the fence post line. Upper and lower horizontal railings 42 and 44 are passed through the rail sleeves and anchored at each corner post. Strips 45 are looped over the lower railing 44 at spaced intervals and strung through the top links of the fencing material 16 to tightly bind the fencing to the lower railing.

Lastly, scrollwork units 46 are mounted between the upper and lower railings 42, 44 by means of C-clamps 48 which are bent around the railings.

The resulting fence structure is attractive and strong and is a fence that would be most acceptable to home owners.

It is to be understood that the form of the invention herewith shown and described is to be taken as a preferred example of the same, and that various changes in the shape, size and arrangement of components may be resorted to without departing from the spirit of the invention or the scope of the claim.

I claim:

25 A fence structure comprising; an aligned plurality of vertical fence posts having their lower ends embedded in the ground; chain link fencing mesh extending along the line of fence posts and fastened thereto, said fencing mesh vertically positioned from adjacent the ground to 30 adjacent the upper ends of said fence posts; a plurality of rail support caps seated upon said fence posts, each said rail support cap having a lower seat portion and an upper vertical rail support portion, said rail support portion having an I-beam shaped mid-section and enlarged 35 top and bottom portions each having equal diameter cylindrical rail openings formed therein; two horizontal continuous equal diameter tubular railings positioned through the rail openings in said rail support caps, the cylindrical interior surfaces of said rail openings dimensioned to provide a sliding fit and firm support to said 40 continuous rails; sections of decorative scrollwork disposed between said continuous railings; and means for fastening said scrollwork to said railings.
